UNITED STATES PATENT OFFICE.

GUY H. BUCHANAN, OF ROSELLE, NEW JERSEY, ASSIGNOR TO AMERICAN CYANAMID COMPANY, OF NEW YORK, N. Y., A CORPORATION OF MAINE.

PROCESS OF RECOVERING HYDROCYANIC ACID.

1,317,755.

Specification of Letters Patent.

Patented Oct. 7, 1919.

Application filed May 7, 1919. Serial No. 295,299.

To all whom it may concern:

Be it known that I, GUY H. BUCHANAN, a citizen of the United States, residing at Roselle, in the county of Union and State of New Jersey, have invented certain new and useful Improvements in Processes of Recovering Hydrocyanic Acid; and I do hereby declare the following to be a full, clear, and exact description of the invention, such as will enable others skilled in the art to which it appertains to make and use the same.

This invention relates to a process of recovering high grade hydrocyanic acid from a crude form of cyanid, and has for its object to provide a method of obtaining such high grade product from low grade raw materials which will be more efficient and less costly than those heretofore proposed.

With these and other objects in view the invention consists in the novel steps and combinations of steps constituting the process, all as will be more fully hereinafter disclosed, and particularly pointed out in the claims.

In order that the precise nature of this invention may be the more clearly understood it is said:—

It is well known in the art that when the ordinary sodium or potassium cyanid of commerce, containing say 96-98% of the corresponding cyanid, is treated with a strong mineral acid, hydrocyanic acid is evolved and a corresponding sodium or potassium salt of the mineral acid used is left behind in the residue. For instance, in the case of sodium cyanid and sulfuric acid, the reaction takes place according to the well known equation—

The usual method heretofore employed of carrying out this operation was to place in a closed vessel a quantity of sulfuric acid, of a strength varying from comparatively dilute acid up to 66° Baumé, although the majority of operators prefer the more dilute acid. It was then the practice to drop powdered or lump cyanid into the acid, the lump form being preferred, as yielding somewhat more hydrocyanic acid than the powdered

form, especially when the cyanid is not substantially pure.

Later developments, however, in this art have shown it practical to dissolve the pure forms of cyanid in water and to then add the solution to the sulfuric acid in a suitable generating vessel.

This practice which has been quite highly developed since the outbreak of the European war, has shown efficiencies of hydrocyanic acid production upward of 75% but rarely have efficiencies as high as 85% been obtained in long practice, and published reports of recent work in connection with poison gas have shown less than 80% for standard practice.

In the present invention I propose to use a crude or impure form of cyanid made from cyanamid and which may be considered to contain approximately 35% sodium cyanid, 40% calcium chlorid, 5% sodium chlorid, 15% of lime and 5% of miscellaneous impurities coming from the cyanamid and playing no essential part in the operation. When this said crude cyanid material is treated in the same manner as the pure cyanid, extremely poor results are obtained, the yield of hydrocyanic acid gas being usually less than 70% and in many instances as low as 50%. The said crude cyanid cannot be dissolved completely in water because it contains a considerable percentage of insoluble lime and other impurities, and further, if one attempts to prepare a solution the hydration of the lime causes the evolution of considerable heat, and it is well known that hot solutions of cyanid rapidly and spontaneously decompose.

Upon the treatment of this crude cyanid with a mineral acid, such as sulfuric acid, there is a considerable production of insoluble sulfate of lime which clogs the apparatus and gives trouble in the generator. This is also true if the same strength of cyanid solution is made from the crude cyanid as is commonly used in the case of the pure cyanid. In general it is most unsatisfactory to attempt to handle the crude cyanid in the same manner and in the same apparatus as is used in the pure cyanid.

The common practice heretofore recommended for the production of prussic acid involves the running of a solution of cyanid into the sulfuric acid. In such case, an excess of sulfuric acid is maintained in the generator throughout the major portion of the reaction and this excess acid, for instance, could react upon the chlorids present in the crude cyanid forming hydrochloric acid, 10 which would be evolved along with the prussic acid, and not only contaminate the latter, but also give rise to serious corrosion difficulties in the apparatus used for recovering the prussic acid. It is therefore, necessary 15 in handling the crude cyanid to prevent any such evolution of hydrochloric acid, and the present invention presents a way of successfully using crude cyanid such as described above, for the production of pure prussic 20 acid.

In carrying out the present process, I proceed in the following manner, reference being had to the accompanying drawing forming a part of this specification in which the 25 figure is a diagrammatic sectional view of one form of apparatus suitable therefor:

Into a suitable generating vessel 1 made of acid resisting material, I introduce a predetermined quantity of water, for example, 30 three or four times the weight of the crude cyanid I intend to use, and to this said water I add the said crude cyanid in the form of dry thin flakes such as it occurs on the open market. Or I may charge the dry 35 flakes into the generator and then add to it the requisite quantity of water as indicated above, it not affecting the process as to which method of operation is used. I immediately close up the generator 1 and 40 as rapidly as possible run in the equivalent amount of sulfuric or other mineral acid necessary for decomposing the sodium cyanid in the crude cyanid added. The lime present being a strongly alkaline compound, 45 with a greater affinity for acid than the sodium cyanid, naturally my acid addition must also be ample to take care of the free lime present, but in no case do I add sufficient acid to more than take care of the alkalinity of the solution, and the sodium cyanid 50 present, although a small excess of sulfuric acid is not harmful if this said excess is not too great. It is not necessary to add sufficient acid to decompose the chlorids completely or 55 in fact in any considerable part. For example, the common practice in carrying out the prior process above mentioned is to add one part 66° Bé. sulfuric acid to one part 96-98% sodium cyanid; whereas in the case 60 of crude cyanid, on account of its alkalinity, my acid addition amounts to approximately 1½ times as much as is used in the case of pure cyanid for the same content of sodium cyanid.

65 The acid is run in quite rapidly through

a supply pipe 2, consuming less than ten minutes for a charge of as much as 500 pounds of crude cyanid at an operation. The solution in the generator heats up and a considerable quantity of prussic acid is 70 evolved and passes out through a pipe 3 to the recovery apparatus, not shown. The rest of the prussic acid generated dissolves in the bulk of the solution used and I find it a simple matter to drive this out by the direct introduction of a very small quantity of steam which is forced from a pipe 4 through the solution in the generator. By operating in this way, I have repeatedly obtained 93% recovery of hydrocyanic acid 80 in fairly concentrated form and have at times obtained as much as 95%. These recoveries are considerably above those obtained in the older process operating on pure cyanid. 85

To avoid the contamination of the hydrocyanic acid by hydrochloric acid I make the acid addition at the bottom of the generator and underneath the surface of the emulsion of crude cyanid and water present. In this way I always have present an excess of unreacted cyanid which would be decomposed by any hydrochloric acid set free in the bottom of the apparatus and consequently I obtain hydrocyanic acid practically free from hydrochloric acid. In many experiments I have found no hydrochloric acid or at most traces in undeterminate quantities in my recovered hydrocyanic acid. To insure absolute freedom from even traces of hydrochloric acid, I may insert in the pipe line 3 conveying the hydrocyanic acid to the recovery plant lumps of lime stone 5 which absorb the hydrochloric acid and do not react upon hydrocyanic acid. This apparatus is simple and easy to maintain and the consumption of lime stone for long time operation is practicably negligible. I am aware that it has been proposed to steam jacket generators for making hydrocyanic acid but I have found it a very decided improvement to directly introduce live steam in the generator and I thereby ascribe my extremely high recoveries in part to this introduction of live steam directly into the 100 generator. 110

The hydrocyanic acid produced by the present method of generation is of essentially the same composition as that produced from pure cyanid, both in concentration and in purity. It may be recovered by absorption, or preferably by condensation at low temperatures, thereby obtaining a solution of hydrocyanic acid of 75% or more concentration. If still purer acid is 120 preferred it is a simple matter to redistil this recovered hydrocyanic acid and condense as pure acid, or it is possible to combine the limestone scrubber with a distilling column or to insert both a limestone scrubber 125 130

and a rectifying column in the pipe line 3, carrying the prussic acid from the generator to the condenser. In this way, it is possible to obtain in one operation practically pure 5 hydrocyanic acid gas.

It is obvious that those skilled in the art may vary the details of the above procedure without departing from the spirit of the invention, and therefore, I do not wish to be 10 limited to the above disclosure except as may be required by the claims.

What I claim is:

1. The process of producing hydrocyanic acid from raw material containing a substantial percentage of impurities, which consists in mixing said raw material with water; subjecting said mixture to the action of a mineral acid introduced beneath the surface of said mixture, whereby hydrocyanic acid gas is evolved; subjecting said mixture to the direct action of steam, whereby any gas which may be dissolved in said mixture is driven off; passing the evolved gas through a scrubber; and suitably recovering 25 said hydrocyanic acid gas, substantially as described.

2. The process of producing hydrocyanic acid from crude cyanids derived from cyanamid and which contain a substantial percentage of insoluble impurities, which consists in mixing said crude cyanids with water to form an emulsion; introducing sulfuric acid beneath the surface of said emulsion, whereby hydrocyanic acid gas is 35 evolved; passing live steam through said emulsion to drive off any of the evolved gas which may be dissolved therein; passing said gas through a scrubber; and suitably recovering said hydrocyanic acid gas, substantially as described.

3. The process of producing hydrocyanic acid from crude cyanids which contain a substantial percentage of impurities in the form of chlorids which consists in mixing 45 said crude cyanids with water; subjecting said mixture to the action of sulfuric acid introduced beneath the surface thereof, whereby hydrocyanic acid gas is evolved and any hydrochloric acid produced is 50 caused to react with the cyanids present; passing steam through said mixture to drive off any of the evolved gas which may be dissolved therein; and collecting and treating said evolved gas to remove any hydrochloric acid passing over therewith, substantially as described.

4. The process of increasing the yield of substantially pure hydrocyanic acid obtainable from low grade cyanids derived from 60 cyanamid and which contain alkaline impurities which consists in mixing said low grade cyanids with water; adding to said mixture a sufficient quantity of a mineral acid to substantially neutralize the same 65 and to decompose the cyanid present, driv-

ing off hydrocyanic acid gas; passing steam through the said mixture to drive off any of the said gas which may be dissolved therein; suitably treating the said gas to remove any impurities therefrom; and suitably recovering the said treated gas, substantially as described.

5. The process of producing substantially pure hydrocyanic acid from low grade cyanids which contain a substantial percentage 75 of impurities in the form of chlorids and lime which consists in mixing said low grade cyanids with water; treating said mixture with a sufficient quantity of sulfuric acid to neutralize the lime present 80 and to decompose the cyanids to evolve hydrocyanic acid gas; introducing steam below the surface of said mixture to drive off any of the evolved gas which may be dissolved therein; passing said evolved gas 85 through a scrubber to remove any foreign acid impurity present; and suitably recovering the said gas, substantially as described.

6. The process of producing hydrocyanic acid from low grade cyanids which contain a substantial percentage of impurities in the form of chlorids and lime which consists in mixing said low grade cyanids with water to form an emulsion; treating said emulsion with a sufficient quantity of sulfuric acid to neutralize the same and to react with the cyanids present to evolve hydrocyanic acid gas, the said sulfuric acid being introduced below the surface of said emulsion whereby any hydrochloric acid 95 produced is caused to react with said cyanids; introducing steam below the surface of said emulsion to drive off any of the hydrocyanic acid gas which may be dissolved therein; passing said gas through a lime stone scrubber to remove any hydrochloric acid contained therein; and suitably recovering said 100 gas, substantially as described.

7. The process of producing hydrocyanic acid from low grade cyanids which contain a substantial percentage of impurities in the form of chlorids and lime which consists in mixing said low grade cyanids with water to form an emulsion; treating said emulsion with a sufficient quantity of sulfuric acid to neutralize the same and to react with the cyanids present to evolve hydrocyanic acid gas, the said sulfuric acid being introduced below the surface of said emulsion whereby any hydrochloric acid 115 produced is caused to react with said cyanids; introducing steam below the surface of said emulsion to drive off any of the hydrocyanic acid gas which may be dissolved therein; passing said gas through a rectifying 120 column; and suitably recovering said gas, substantially as described.

8. The process of producing hydrocyanic acid from low grade cyanids which contain a substantial percentage of impurities in 130

the form of chlorids and lime which consists in mixing said low grade cyanids with water to form an emulsion; treating said emulsion with a sufficient quantity of sulfuric acid to neutralize the same and to react with the cyanids present to evolve hydrocyanic acid gas, the said sulfuric acid being introduced below the surface of said emulsion whereby any hydrochloric acid produced is caused to react with said cyanids; introducing steam below the surface of said emulsion to drive off

any of the hydrocyanic acid gas which may be dissolved therein; passing said gas through a combined limestone scrubber and rectifying column; and suitably recovering 15 said gas, substantially as described.

In testimony whereof I affix my signature, in presence of two witnesses.
